CLAIM

The ornamental design for makeup glasses, as shown and described.

DESCRIPTION

FIG. 1 is a perspective view of the makeup glasses, showing our new invention,

FIG. 2 is a front view of the same,

FIG. 3 is a side view of the same,

FIG. 4 is a top view of the same,

FIG. 5 is a front view of the same while in use; and,

FIG. 6 is a side view of the same while in use.

The broken lines in the drawings depict the use environment of the makeup glasses that form no part of the claimed design.
